PRESS FOR RUBBER FOOTWEAR

Alois Bánovský, Zlin, Czechoslovakia, assignor to
Bata, národní podnik, Zlin, CzechoslovakiaApplication April 28, 1947, Serial No. 744,284
In Germany October 9, 1944

7 Claims. (Cl. 18—17)

1

In the known process for the pressing of a shoe sole and simultaneously vulcanizing it on to a prepared upper (as distinct from ordinary pressing when the pressure of the press on the workpiece acts in a single direction only) the sole and the upper, and if desired also the heel, are exposed simultaneously to pressure in two directions at right angles to one another.

The presses employed hitherto for carrying out this process have been either purely hydraulic, i. e. equipped with two plungers arranged at right angles to one another, or mechanical with a system of levers driven hydraulically or pneumatically or by an electric motor.

With the known mechanical presses the two pressures acting at right angles to one another are produced by a complicated system of transmissions and levers. On the other hand the purely hydraulic presses have the disadvantage of heavy weight and of depending upon a source of liquid under pressure. Similarly the mechanical presses, if driven hydraulically or pneumatically, are dependent upon a source of pressure fluid. Mechanical presses driven by electric motors are prone to break-downs in operation very frequently due to the complication of the transmission.

An object of the present invention is to eliminate these disadvantages of the known presses for the pressing of shoe soles made of rubber and the like and the simultaneous vulcanization of the soles to the finished uppers.

To the attainment of this object the invention provides a novel arrangement allowing the use of much lighter and simpler press components and characterized in that the pressures necessary for the pressing operation acting in two directions at right angles with respect to one another are produced by means of a loop or rigid frame equipped with arms pivoted thereon. The two pressures acting at right angles with respect to one another are then produced simply by shifting the loop or rigid frame relatively to the workpiece during which shifting movement the said arms are made to act one against the other, the shoe sole moulding portion being brought into position for pressing at the same time.

The foregoing and further advantageous features of the invention will become clear from the following description of one exemplified embodiment illustrated on the accompanying drawings, whereon—

Fig. 1 shows diagrammatically, in perspective

2

and partly in section, one embodiment of a pressing device according to the invention;

Fig. 2 shows a detail of Fig. 1 on a larger scale, namely the ball joint of the mould core; and

Fig. 3 shows another detail of Fig. 1, on a larger scale, namely, the attachment of the switch.

The whole of the stresses occurring in the course of the pressing process are carried by a loop or rigid frame 1, the threaded spindles 2, 2', the base plate 3, and the linked arms 4, 4'. The threaded spindles 2 move the loop or rigid frame 1 in a downward direction when pressing, i. e. when closing the press, and in an upward direction when opening the press. Heated holding pieces 5, 5' are pivoted to the arms 4, 4' and supported from the base plate 3 by pivotally connected rods 6, 6' on opposite sides of the workpiece support 11 and last 10. Each of the heated holding pieces 5, 5' forms, together with the rods 6, 6', a parallelogram link system which carries the lateral moulding jaws 7, 7' and transmits to them the heat required for the operation. The moulding jaws 7, 7', together with the press plunger 8 penetrating between them from above, constitute the operative components proper of the press, in place of a box-shaped pressing mould as hitherto used.

When the arms 4, 4' that are pivoted on the loop 1 are lowered and raised, respectively, they cause the approachment and separation, respectively, of the holding pieces 5, 5' together with the moulding jaws 7, 7', the press plunger 8 being alternatively interposed between and withdrawn from the said moulding jaws.

The press plunger 8 is attached to a heating plate 9 which is carried by the loop or rigid frame 1 and takes part in its movements described above, i. e. downward when pressing, and upward when opening the press.

The shoe last 10 forming the core of the mould is arranged at the upper end of a support column 11 whose lower reduced end 13 is equipped with a ball 12 which forms a ball joint with the components 13, 14, 15. See also Fig. 2. The reduced end 13 of column 11 has such a clearance in the hole of component 14 that the last 10 remains in an erect position, the clearance being very small, that is, of the order of approximately 0.3 mm.

The purpose of the ball joint is to permit, when the press is closed, correct location of the last in the mould. The last has substantially a correct shape according to the jaws 7 and 7' but during assembly and by action of heat certain inaccuracies, though small, arise in the location of

the last and these inaccuracies have an unfavorable effect on the product when anchoring the last. The mentioned ball joint is pushed into the guide groove (preferably of T-shaped cross section) of a support component 16 of the device and admits an independent adjustment of the last 10 between the jaws 7, 7'. The component 15 constitutes a slide which is displaceable in proportion to the orbital movement of last 10 on the upper end of the workpiece support or column 11 to operate electric switch 24 when the last is adjusted to the proper position between the jaws 7, 7' to initiate operation of the electric motor which drives the shaft, gear and pinion system for revolving the spindles 2, 2' for displacing the frame 1. In order to properly center the last 10 with respect to the jaws 7, 7', the workpiece support or column 11 is grasped and adjusted in a substantially orbital path until last 10 is correctly centered with respect to jaws 7, 7', at which time the motor is activated through the proper position of the lever 25 to actuate electric switch 24.

Advantageously the drive of the pressing device is effected by means of the two threaded spindles 2, 2' through helical gears 17, 18 and bevel gearing 19, 20 from a motor (not shown) driving the shaft 21 of the bevel pinion 20.

The course of operations is as follows:

The last 10, which has been prepared for pressing and which forms a unit with the ball joint components 12 to 15, is pushed into the guide of the component 16 of the machine, together with the uppers of the shoe fitted to it and with the required rubber plates put on at the sole portion. In the correct position of the last the supply of electric current is switched on by means of an electric switch 24 (see Fig. 3) of known design, and thereby the starting of the driving motor, i. e. the initiation of the pressing operation, is made possible. The electric switch is actuated by lever 25 when the support 15 is in the correct position. The motor then turns the shaft 22 by means of the shaft 21, through the bevel gearing 19, 20, and sets the two threaded spindles 2, 2' in rotary motion through the worm gears 17, 18. These threaded spindles 2, 2', by means of the threads in the eyes 23, 23' of the loop or rigid frame 1, draw the latter down towards the moulding last 10, the linked arms 4, 4' being thereby turned from the oblique position shown in Fig. 1 into a substantially horizontal position, i. e., until they are approximately parallel to the loop or rigid frame 1 in which position the maximum pressing force is produced by the lever action. The holding pieces 5, 5' of the lateral moulding jaws 7, 7' follow the aforesaid movement of the arms 4, 4'; they remain, however, constantly in a horizontal position through the action of the rods 6, 6', and press the mould jaws 7, 7' against the last 10. Simultaneously with the lowering of the loop or rigid frame 1 the plunger 8, equipped with a (negative) impression of the sole, approaches the last 10 from above. This plunger 8 is fixed in known manner on a spring-supported heating plate 9. As soon as the jaws 7, 7' reach abutting position and simultaneously with the insertion of the plunger 8 between them, the loop or rigid frame 1 which has reached in the meantime its lowest position causes by its action the switching-off of the current, preferably automatically by means of an electric switch, whereby the pressing device comes to a standstill in the closed position. After the lapse of

the period required for the vulcanizing of the rubber the device is set in motion again automatically in known manner, and the press is opened. After taking out the last, pulling-off 5 the finished shoe and fitting-on a new prepared upper, the process is repeated as described.

It is, of course, possible to arrange the loop or rigid frame 1 in which all stresses converge, in a special guide, or to use an alternative 10 driving mechanism instead of the threaded spindles 2, 2'. Further, it is within the scope of the invention to have the loop or rigid frame 1 remain stationary when closing the press and move the base plate 3 together with the mould 15 last 10 and the other components with respect thereto.

I claim:

1. A device for pressing and vulcanizing on workpieces consisting of soles and heels of 20 rubber-like footwear, comprising a base, a pair of vertically extending spindles mounted in spaced positions on said base, screw-threads formed on the upper ends of said spindles, a rigid frame having screw-threaded apertures 25 adjacent opposite ends thereof engaged by the screw-threads on said spindles, said frame being bodily displaceable on said spindles, arms pivotally mounted between the sides of said frame adjacent opposite ends thereof, a workpiece engaging member pivotally connected with each arm, means supporting said workpiece engaging members from said base, a workpiece support extending from said base, and a last carried by said workpiece support in a position between 30 said workpiece engaging members whereby the workpieces on said last may be subjected to pressure by displacement of said workpiece engaging members against the workpieces.

2. A device as set forth in claim 1 in which 40 said arms are so dimensioned that bodily displacement of said rigid frame on said spindles automatically effects pivotal displacement of said arms through a sufficient distance to move said workpiece engaging members into a position for 45 automatically engaging or disengaging the workpiece with respect to said last.

3. A device as set forth in claim 1 in which 50 said workpiece engaging members comprise heated holders and wherein said means supporting said workpiece engaging members are constituted by pivoted parallelogram links pivotally connected with said base at their lower ends and pivotally connected with said workpiece engaging members at their upper ends.

4. A device as set forth in claim 1 in which 55 said workpiece support is adjustably mounted on said base by a ball joint which permits orbital adjustment of said last with respect to said workpiece engaging members.

5. A device as set forth in claim 1 in which 60 said workpiece engaging members comprise heated holders and wherein a shaped jaw is interposed between each heated holder and one side of the last, the means supporting said workpiece engaging members on said base comprising parallelogram links connected at spaced positions on said base and at spaced positions below said workpiece engaging members, said 65 workpiece support being connected through a ball joint at its lower end with said base in a position between the pivotal connections of said parallelogram links with said base for permitting orbital adjustment of the last carried by 70 said workpiece support between said jaws for

facilitating the operation of said jaws against workpieces positioned on said last.

6. A device as set forth in claim 1 in which said spindles are connected through gearing with drive means carried by said base, and means for controlling the operation of said drive means when the workpiece support is adjusted to a position centering said last with respect to the workpiece engaging members.

7. A device as set forth in claim 1 which includes an orbital joint between the lower end of said workpiece support and said base, said orbital joint being seated in a displaceable slide, a control switch operative by displacement of said slide to a position corresponding to a position in which said last is centered with respect

to said workpiece engaging members, and motor means for rotatably driving said spindles under control of said control switch.
